UNITED STATES PATENT OFFICE.

DANIEL W. DELANEY, OF NEW YORK, N. Y., ASSIGNOR TO ALFRED B. MARX AND GEORGE E. MARX, OF SAME PLACE.

DESIGN FOR A BILLIARD-TABLE.

SPECIFICATION forming part of Design No. 32,835, dated June 12, 1900.

Application filed April 19, 1900. Serial No. 13,550. Term of patent 7 years.

To all whom it may concern:

Be it known that I, DANIEL W. DELANEY, a citizen of the United States, residing at the city of New York, in the county and State of

5 New York, have invented and produced a new and original Design for Billiard-Tables, of which the following is a specification, reference being had to the accompanying drawings, forming part thereof, in which—

10 Figure 1 is a perspective view representing my new design. Fig. 2 is an elevation, and Fig. 3 a broken cross-section at one edge of the table.

As shown in the drawings, the leading or 15 material features of my design consist of the long ogee-curved surface of the broad rail and heads of the body of the billiard-table and the short ogee-curved surface of the cushion-rails. The heads *a* at the respective 20 opposite ends of the table and the broad rails

b, extending between the same, are provided with long ogee-curved surfaces *2*, comprising the vertical surface of the heads and broad rails.

The cushion-rails *c*, comprising the sides 25 and ends of the table, are made with short ogee-curved surfaces *3*.

The frieze ornament *d* extends downward around the table below the bases of the heads and broad rails, and the said frieze is ornamented in empire-style carving.

The legs *e* are fluted, substantially as shown.

What I claim is—

The design for a billiard-table, substantially as shown and described.

Signed by me this 14th day of April, 1900.

DANIEL W. DELANEY.
